UNITED STATES PATENT OFFICE

160,009

RECEPTACLE FOR SCOURING PADS OR SIMILAR ARTICLE

Lillian E. Parker, Brighton, Mass.

Application July 30, 1949, Serial No. 4,226

Term of patent 14 years

(Cl. D9—2)

To all whom it may concern:

Be it known that I, Lillian E. Parker, a citizen of the United States of America, residing in Brighton, in the county of Suffolk and Commonwealth of Massachusetts, have invented a new, original, and ornamental Design for a Receptacle for Scouring Pads or Similar Article, of which the following is a specification, reference being had to the accompanying drawings forming a part thereof.

Fig. 1 is a side elevation of a receptacle for scouring pads or similar article, showing my new design;

Fig. 2 is a plan view thereof; and
Fig. 3 is a bottom view thereof.

The dominant features of my design reside in those portions shown in full lines.

I claim:

The ornamental design for a receptacle for scouring pads or similar article, substantially as shown and described.

LILLIAN E. PARKER.
